Assistant Examiner — Alison Davis

(57) **CLAIM**

The ornamental design for a video frame, as shown and described.

DESCRIPTION

FIG. 1 is a top-front-left perspective view of a video frame showing my new design;

FIG. 2 is a bottom-front-left perspective view thereof;

FIG. 3 is a top-rear-right perspective view thereof;

FIG. 4 is a bottom-rear-right perspective view thereof;

FIG. 5 is a front elevational view thereof;

FIG. 6 is a rear elevational view thereof;

FIG. 7 is a top plan view thereof;

FIG. 8 is a bottom plan view thereof;

FIG. 9 is a right elevational view thereof;

FIG. 10 is a left elevational view thereof; and,

FIG. 11 is a cross-sectional view taken along line 11-11 in FIG. 6.

The broken lines showing a screen surface and a label surface in FIGS. 1, 2, 5, and 11, and the broken lines showing a charging port and a power button in FIGS. 2-4, 6, 8, and 11 are included for the purpose of illustrating environmental structure and form no part of the claimed design.

1 Claim, 11 Drawing Sheets
